UNITED STATES PATENT OFFICE

2,531,256

SASH LOCK

Charles B. Clasen, Reno, Nev.

Application December 26, 1947, Serial No. 793,867

1 Claim. (Cl. 292—340)

1

This invention relates to window sash locks.

An object of this invention is to provide a sash lock for mounting on a pair of sash members which includes a pivoted bolt adapted to be secured to one of the sash members, and a keeper adapted to be secured to the other of the sash members, the keeper being formed with a horizontal slot having a flared mouth, so that engagement of the bolt in the slot will effect endwise movement of the sash members to tightly closed position.

A further object of this invention is to provide a sash lock which can be made out of metal, plastic or a combination of these elements.

A further object of this invention is to provide a sash lock which is of simple construction so that it can be formed out of cast or molded material.

To the foregoing objects, and others which may hereinafter more fully appear, the invention consists of the novel construction, combination and arrangement of parts, as will be more specifically referred to and illustrated in the accompanying drawings, but it is to be understood that changes, variations, and modifications may be resorted to which fall within the scope of the invention as claimed.

In the drawing:

Figure 1 is a plan view partly broken away of a sash lock constructed according to an embodiment of this invention.

Figure 2 is a sectional view taken on the line 2—2 of Figure 1.

Figure 3 is a sectional view taken on the line 3—3 of Figure 1.

Figure 4 is a sectional view taken on the line 4—4 of Figure 2.

Figure 5 is a detailed end elevation of the sash lock removed from the sash.

Referring to the drawing, the numeral 10 designates generally a block or base which is adapted to be secured by fastening means 11 to the upper side of the lower rail 13 of an upper sash 12. The body or block 10 is formed with a slot 14 extending horizontally through the inner edge of the block 10 and also through one end thereof. The block 10 on the lower side thereof has projecting therefrom a pair of tangs or points 15 which with the fastening means 11 are adapted to hold the block 10 against movement on the rail 13.

A swingable bolt or bar 16 is loosely disposed in the slot 14 being pivoted on the fastening member 11. An inner block or keeper 17 is disposed on the upper side of the upper rail 18 of a lower

sash 19. The inner block or keeper 17 is secured to the rail 18 by means of a screw 20 which has the head thereof countersunk in an opening 21 formed in the keeper 17. The keeper 17 is formed with a horizontally disposed keeper slot 22 which extends entirely through the block 17 and through one edge thereof. The slot 22 is flared upwardly as at 23 on one end of the block 17 and is also flared downwardly as indicated at 24. The block 17 is formed with an arcuate or cam shaped inner edge 25 so that when the bolt 16 is swung into the slot 22 the knob 26 which is fixed to the free end of the bolt 16 will bear against the curved inner edge 25 of the keeper block 17 so as to apply increased pressure between the two blocks 16 and 17 as the bolt 16 is swung to substantially a right-angular and completely locking position.

The keeper block or body 17 is also formed with a pair of downwardly projecting tangs 27 which are adapted to pierce the upper side of the rail 18 so that when the single screw 20 is in applied position the keeper block 17 will be firmly held against turning movement with respect to the rail 18.

In the use of this sash lock the two members 10 and 17 are secured by the fastening means 11 and 20 to the respective rails 13 and 18. When it is desired to raise or lower one of the sashes, the bolt 16 is swung to a position overlying the lower rail 13 of the upper sash 12. In locking the two sashes together these sashes are moved to their extreme upper and lower positions so that the upper sides of the rails 13 and 18 will be substantially coplanar. In the event there is a slight variation in the initial positioning of the windows including the rails 13 and 18 when the bolt 16 is swung to locking position this bolt will engage one of the flared surfaces 23 or 24 of the keeper block 17 and further inward movement of the bolt 16 will effect vertical movement of the sashes one relative to the other and at the same time the rails 13 and 18 will by reason of the engagement of the knob 26 with the cam surface 25 be drawn tightly together.

I claim:

In a sash lock a keeper block adapted to engage on the upper side of the upper rail of a lower sash, said keeper block having a horizontal keeper slot opening through the inner and outer edges and one end thereof, the walls of said slot being flared at said one end of said block for receiving and guiding a locking bolt slidably therein, a vertical bore extending through said block in the center thereof and intersecting said slot,

an upwardly opening counterbore of increased diameter formed in said block concentric with said first bore and extending below said slot, and a plurality of spaced apart tangs depending from the bottom of said block for engagement in the upper rail whereby a single headed fastening means may be disposed in said bore and counterbore for securing said block to the upper rail and said tangs will prevent turning of said block about the fastening means.

CHARLES B. CLASEN.
